DESIGN FOR A CONDUIT FOR A CONDUCTOR SYSTEM

Elmer T. Carlson, Fort Mitchell, Ky., assignor to The Trumbull Electric Manufacturing Company, Plainville, Conn., a corporation of Connecticut

Application March 1, 1941, Serial No. 99,282

Term of patent 14 years

To all whom it may concern:

Be it known that I, Elmer T. Carlson, a citizen of the United States, residing at Fort Mitchell, Kenton County, and State of Kentucky, have invented a new, original, and ornamental Design for a Conduit for a Conductor System, of which the following is a specification, reference being had to the accompanying drawing, forming part thereof.

Fig. 1 is a perspective view of a conduit for a conductor system showing my new design.

Fig. 2 is an enlarged diagrammatic outline of a section taken through one wall of the conduit.

The appearance of the wall of the conduit not fully shown is conventional. The present design is characterized by the wedge shaped moulding which extends along opposite walls of the conduit.

I claim:

The ornamental design for a conduit for a conductor system, as shown and described

ELMER T. CARLSON.
